UNITED STATES PATENT OFFICE.

JACOB E. MALZI, OF MIDDLETOWN, PENNSYLVANIA.

ATTACHMENT FOR RIVETING HAMMERS.

1,410,696.

Specification of Letters Patent. Patented Mar. 28, 1922.

Application filed May 12, 1920. Serial No. 380,936.

To all whom it may concern:

Be it known that I, JACOB E. MALZI, a citizen of the United States, residing at Middletown, in the county of Dauphin and State of Pennsylvania, have invented certain new and useful Improvements in Attachments for Riveting Hammers, of which the following is a specification.

This invention relates to an improved 10 guard especially adapted for use on riveting hammers.

A principal aim of this invention is to provide a guard for pneumatic riveting hammers which when applied to the forward portions of a pneumatic riveting hammer will effectively prevent sparks and hot metal chips upon leaving the rivet head being formed, from striking and possibly causing serious injury to the operator. More 15 particularly, the invention herein disclosed is especially adapted for use when forming the head on a rivet underneath or below the pieces being fastened together. Of course, when forming the head of a rivet on the 20 under side of a plurality of metal sheets or the like, the operator must naturally position himself below the rivet with the result that sparks and hot scale or chips upon leaving the rivet head strike the operator's 25 arms, hands and very often scatter in the air to such an extent that sparks and small hot chips fly into the eyes.

A further object of the invention is to provide a guard for pneumatic riveting hammers which may be readily moved rearwardly or out of the way of the operator when finishing the head of the rivet.

A further object of the invention is to provide a guard for pneumatic hammers 40 having novel means whereby the action of the plunger head of the hammer may be conveniently viewed without the possibility of sparks or chips flying into the eyes or other parts of the operator's person.

A further object of the invention is to provide a guard of the class described which may be readily applied to pneumatic riveting hammers and which is desirable in use and cheap to manufacture.

50 Other objects and advantages of the in-

vention will be apparent during the course of the following description.

In the accompanying drawings forming a part of this application and in which like numerals are employed to designate like parts throughout the same,

Figure 1 is a side elevation of the improved guard in an operative position on a riveting hammer,

Figure 2 is a similar view of the improved 60 guard, the same being shown in an inoperative position,

Figure 3 is a horizontal section through the improved guard, the view being taken on line 3-3 of Figure 2,

Figure 4 is a perspective of the device detached,

Figure 5 is a central vertical longitudinal sectional view through the device.

In the drawings wherein for the purpose 70 of illustration is shown a preferred embodiment of the invention, the numeral 10 generally designates a pneumatic riveting hammer which is inclusive of a barrel 11 having a longitudinally extending bore 12 75 within which the usual piston reciprocates for operating a longitudinally movable plunger 13. As illustrated particularly in Figures 1 and 2, the longitudinally movable plunger 13 is formed with an enlarged 80 head 14 having a concaved recess within which the head of a rivet 15 is received as the plunger is forced into engagement with the rivet. In this case, the rivet 15 is illustrated as being extended through sheets of 85 metal 16 and 17 though it is obvious that the rivet may be employed for connecting other elements. While the head of the rivet is being formed the rivet is held in position by an anchoring member 19.

The improved guard generally designated by the numeral 20 consists of a cylindrical attaching portion 21 adapted to be slidably arranged about the forward portion of the barrel 11. The cylindrical attaching portion of the guard is preferably of leather or other yieldable material so that the same will snugly engage the barrel of the hammer and will not partake of any great amount of movement as the result of vibration. As il- 90 95 100

lustrated in Figure 5, the cylindrical attaching portion 21 is formed from a single length of leather having its end portions overlapped and connected by spaced rivets or fastening 5 devices 22.

Secured to the outer side of the forward portion of the attaching sleeve 21 is a cylindrical protector 24 which is preferably formed from galvanized iron having its end 10 portions overlapped and connected by rivets 26. It will be noted that the forward rivet 22 of the attaching sleeve 21 is also extended through the rear portion of the cylindrical protector 24 so that the parts are securely 15 connected. Additional rivets 28 are also extended through the overlapped portions of the sleeve 21 and protector 24 so that the cylindrical protector is securely attached to the sleeve. The forward portion of the 20 cylindrical protector 24 is provided with a plurality of transverse openings or ports 29 over which pieces of copper screening 30 are extended. With reference to Figure 5, it will be observed that the screens 30 are secured to the inner side of the cylindrical protector 34 so that the outer side of the protector will not be possessed of any objectionable projections. The forward portion of the cylindrical protector 24 is beaded or 25 rolled inwardly, as indicated at 32, so as to present a flat bearing surface to the adjacent piece of metal through which the rivet is extended.

In the use of this device, the attaching 35 sleeve 21 is positioned about the forward portion of the barrel 11 so that the cylindrical protector 24 will surround the enlarged head 14 of the plunger and the extended portion of the rivet. During the 40 initial hammering of the extended portion of the rivet, sparks and frequently hot chips of metal leave the rivet and possibly strike the operator. This is especially true when upper cutting rivets, that is when employing 45 the pneumatic riveting hammer to form the head on a rivet underneath or below the piece or pieces being fastened together. When driving rivets in this manner the sparks and hot scale or chips which fall 50 strike the operator's arms, hands and very often lodge in the eyes of the operator with disastrous results. With the employment of this device the sparks and hot chips are not allowed to strike the operator or leave the 55 immediate vicinity of the rivet since the screens 30 and the protector 24 effectively intercept all flying matter. When the head of the rivet is being finished, as illustrated in Figure 2, the sleeve may be slipped rearwardly so as to give the operator an unobstructed view of the plunger head and the rivet head. However, while the head is 60 being formed the operator may view the operation through the screens 30. When the 65 nature of the work does not necessitate the

use of the guard, the same may be either entirely removed or slipped rearwardly on the barrel of the hammer out of the way of the operator.

With reference to the foregoing description taken in connection with the accompanying drawings it will be observed that a guard constructed in accordance with this invention will effectively protect the operator against all sparks and chips flying from the rivet during the formation of the head on the same. Also a device constructed in accordance with this invention may be used without interfering with the riveting operation or the rapidity with which the work 80 may be performed.

It is to be understood that the form of the invention herewith shown and described is to be taken as a preferred embodiment of the same and that such minor changes in construction and arrangement of parts may be made as will remain within the spirit of the invention and the scope of what is claimed.

Having thus described the invention, what is claimed as new is:

1. The combination with a riveting hammer, of a guard comprising an attaching member constructed to embrace the barrel of the riveting hammer, and a protector carried by the attaching member and enclosing the plunger and head of the hammer.
2. A guard for riveting hammers comprising an attaching member, and a protector attached to the attaching member and provided with means whereby the riveting 100 operation may be viewed.
3. A guard for riveting hammers comprising a cylindrical attaching member of yieldable material, and a protector carried by said attaching member.
4. A guard for riveting hammers comprising a cylindrical attaching member of yieldable material, and a protector carried by said attaching member, said protector being provided with means whereby the 110 riveting operation may be viewed.
5. A guard for riveting hammers comprising a cylindrical attaching member of yieldable material adapted to be frictionally engaged with the forward portion of the 115 barrel of a riveting hammer, a cylindrical protector carried by said attaching member and provided with a plurality of openings, and foraminous members extending over said openings.
6. A guard for pneumatic riveting hammers comprising a cylindrical attaching member of yieldable material adapted to be adjustably mounted upon the barrel of a riveting hammer, and a protector connected to said cylindrical barrel and provided with means whereby the riveting operation may be viewed.
7. A guard for pneumatic riveting hammers comprising a yieldable attaching mem- 130

ber adapted to be adjustably arranged on the barrel of a riveting hammer, and a cylindrical protector secured to the outer side of said attaching member and having its 5 forward portion beaded.

8. A device of the class described comprising a cylindrical attaching member, a cylindrical protector surrounding the forward portion of the attaching member and

secured to the same, said cylindrical protector being provided with a plurality of openings whereby the riveting operation may be viewed, and foraminous members secured to the inner side of said protector and extending over said openings. 10

In testimony whereof I affix my signature. 15

JACOB E. MAILZI. [L. s.]
